CLAIM

The ornamental design for a combined shoe and shoe device, as shown and described.

DESCRIPTION

FIG. 1 is a perspective view of a combined shoe and shoe device according to my new design, shown in reduced scale; FIG. 2 is a perspective view thereof, shown without the shoe for ease of illustration, with one of the pins in uninstalled condition;

FIG. 3 is a perspective view thereof, shown without the shoe for ease of illustration;

FIG. 4 is a top plan view thereof, shown without the shoe for ease of illustration;

FIG. 5 is a bottom plan view thereof, shown without the shoe for ease of illustration;

FIG. 6 is a front elevation view thereof, shown without the shoe for ease of illustration;

FIG. 7 is a rear elevation view thereof, shown without the shoe for ease of illustration;

FIG. 8 is a right side elevation view thereof, shown without the shoe for ease of illustration; and,

FIG. 9 is a right side perspective view thereof, shown in reduced scale.

The broken lines in the figures illustrate the portions of the design that form no part of the claimed design.
